Nelson M. Howard

UNITED STATES PATENT OFFICE.

LOUIS A. CASGRAIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR APPLYING FOXING TO RUBBER SHOES.

Application filed April 7, 1919. Serial No. 288,229.

To all whom it may concern:

Be it known that I, LOUIS A. CASGRAIN, a citizen of the United States, residing at Beverly, in the county of Essex and State

5 of Massachusetts, have invented certain Improvements in Machines for Applying Foxing to Rubber Shoes, of which the following description, in connection with the accompanying drawings, is a specification, 10 like reference characters on the drawings indicating like parts in the several figures.

This invention relates to the manufacture of rubber footwear such as tennis shoes, sneakers, arctics and the like. The invention 15 is herein set forth with particular reference to the application of foxing such as is employed as an intermediate strip between the edges of the soles and the marginal portions of the uppers of such shoes.

20 Heretofore, so far as I am aware, the application of the foxing has always been effected by hand, requiring the preliminary application of cement to the shoe upper while on the last and then a careful laying

25 of a strip of material suitable for foxing upon the cement and running a roller along the foxing to ensure its proper contact with the cement in order that the later vulcanizing operation may effect a secure and completely waterproof joint. It has been necessary, in order to prepare the foxing for application as above described, first to form the rubber compound into a sheet and then to slit it to form strips, this necessarily requiring 30 the use of a machine for manufacturing the sheet and also requiring an operation of stripping the sheet and then laying the strips between protecting sheets in order that the rubber may not become "dry cured."

35 In another application Ser. No. 288,230, filed by me April 7, 1919, I have disclosed a method and means for making foxing in strip form of uniform width which is coiled with an intercoiled strip of paper or cloth 40 so that the coiled strips of foxing will not stick together.

An important object of the present invention is to avoid the time and expense required for preliminarily forming the sheet 45 of rubber compound and then converting it into strips, and applying the strips by the hand operation above described.

With this object in view, this invention in one aspect comprises applying a foxing

strip of proper width and thickness to the 55 shoe by pressure effected through the medium of a backing strip of non-adhesive material which has been intercoiled therewith.

In the method of applying the foxing as heretofore proposed, it has been customary 60 to produce the appearance of a line of stitches along the edge of the foxing which overlaps the portion of the upper above the shoe bottom, such appearance of stitches being produced by the manual use of a serrated 65 wheel. This requires the expenditure of considerable labor and the necessity of skill to produce a good appearance. An important feature of this invention is that the same power which is employed to feed the 70 strip to position for application to the shoe serves also to form a line of indentations along one margin of the strip of foxing to produce the effect of stitches.

In the drawings, I have illustrated one embodiment of mechanism which I have invented 75 for carrying out my improved method.

In said drawings,

Fig. 1 is a side elevation, partly broken 80 out.

Fig. 2 is a perspective view of portions of the machine shown in Fig. 1, looking from a point somewhat to the left and behind the Fig. 1 view.

Fig. 3 represents a detail section through co-acting portions of the feeding and strip marking rolls or wheels.

85 A frame standard 12 is provided with two arms 13, 14, the former having a shaft or 90 spindle to support the reel 15 which supplies the two-ply strips of foxing *a* and non-adhesive intercoiled paper or cloth strip *b*.

A take-up reel 16 for the strip *b* is rotatably mounted upon one end of an arm 17 95 pivotally connected at 18 to the arm 14 and having a spring 19 so connected to it as to a little more than counterbalance the weight of the reel 16 and the material which may be wound thereupon as hereinafter described. 100 Said spring also serves to co-operate in attaining a friction drive of the reel 16 as hereinafter explained.

105 Mounted in bearings carried by a suitable frame housing 20 is a shaft 21 carrying the upper feed wheel 22 which preferably has flanges as best illustrated in Fig. 3. A lower feed wheel 23, which is also the foxing ap-

plier as hereinafter described is mounted and arranged to be in almost peripheral contact with the wheel 22 and is formed with a peripheral toothed or knurled portion 24 (Figs. 2 and 3) having such shape as to indent or impress the foxing material with a line similar to that which has been heretofore produced by the serrated wheel operated by hand.

10 A brush 25 the bristles of which are in spaced groups is carried by a shaft 26 mounted in suitable bearings substantially at a right angle to the shaft of wheel 23. A pinion 27 carried by shaft 26 meshes with 15 a gear 28 carried by a shaft 29 mounted in suitable bearings provided in the frame of the machine. A suitable guard frame for the gearing 27, 28 is indicated at 30.

The shaft 29 is driven by skew gearing 31, 20 one member of which is carried by the shaft 21.

Power to operate the machine may be applied to the shaft of either of the wheels 22, 23. In Fig. 1, I have illustrated a drive belt 32 fitting a pulley carried by shaft 21. The shaft 21 carries a spur gear 33 meshing with a spur gear 34 carried by the shaft of wheel 23, these two spur gears being indicated by dotted lines in Fig. 1.

30 The shaft of wheel 23 carries a pulley 35 connected by a belt 36 with a pulley 37 which is carried by the shaft or spindle of the take-up wheel 16.

A suitably mounted, and preferably adjustable, guide for the shoe is indicated at 38 in Figs. 1 and 2.

Any suitable means for starting and stopping the machine may be employed such as any preferred form of clutch operated by 40 an arm 39 carried by a rockshaft 40, the latter having an arm 41 to which is connected any suitable treadle rod 42. In producing the supply of material consisting of the intercoiled strips *a* and *b* formed upon a reel 45 such as indicated at 15, the strip of foxing being freshly made and immediately coiled as explained in the application Ser. No. 288,230 hereinbefore referred to, two advantages result. First, the foxing is so protected that it does not need to be used as promptly after making it as has been necessary heretofore where the rubber compound is formed into sheets and then cut into strips. Second, it provides a supply for use 50 as follows:—The two-ply strip *a*, *b*, is led from the reel 15 over the roll 22 between the flanges thereof and under and partly around the wheel 23, the strip of foxing *a* being outermost upon the wheel 23 so that 55 said wheel can serve as the applier to lay the foxing on the proper portion of the shoe upper *c* carried by the last *c*, said upper overlapping the insole *d* as is customary. The operator, holding the last and the shoe 60 parts thereon in his hands, guides it in the

direction of the arrow *x* in Fig. 1 under the wheel 23, employing the guide 38 if desired to insure the location of the stitch indented edge of the foxing at the proper distance from the shoe bottom as indicated in Fig. 2. 70 In practice, it will be preferable to provide the supply reel 15 with sufficient length of the strip *b* longer than the strip *a* so that, when the machine is "threaded up" the end of the strip *b* can be carried up and attached 75 to the take-up reel 16.

As the operator feeds the shoe along as described, whatever amount of upward pressure against the applying wheel 23 as may be necessary will be exerted to cause the 80 stitch indented portion of the foxing to be uniformly and firmly laid in place. As the movement of the work proceeds, the revolving tufts or groups of bristles 25 of the brush act to wipe down the other edge portion of the foxing *a* over that portion of the upper which lies upon the insole. By arranging the brush bristles in separated groups or tufts, such spaces are left between them that the bristles will not interfere 90 with each other as they follow each other around. That is, each tuft or bunch will perform its function without causing such lateral flexing of other bristles as would tend to cause displacement of the edge portion of the foxing which is laid over upon the shoe bottom as described.

The object of the friction drive of the take-up reel 16, by means of the belt 36 in connection with the yielding mounting of 100 carrier 17, 19, is to regulate the tension of the pulley upon the strip *b* which is drawn on to the reel 16 in the direction of the arrow *y*. As the diameter of the winding or coiling upon the spool or hub of reel 16 increases, the belt 36 will slip sufficiently to insure the uniformity of the pull on the strip *b*.

As has been stated, the wheels 22, 23 not only serve by their co-action to feed the two-ply strip but they also co-act to form along one edge of the foxing a line of indentations to imitate stitching. Since said line of indentations is effected by means of the knurled or toothed portion 24 of the wheel 23, the stitch impressions are effected by means of power imparted by the machine itself instead of requiring any manual exertion upon the part of the operator. Of course, to some extent the stitch indentations extend into the intercoiled protecting strip *b* and since the two strips are still together when they reach the point where the shoe is held against them by the operator, the pressure of the work against the applying wheel by the operator does not press out or remove the indentations in the foxing strip *a*.

The two wheels 22, 23 feed the two-ply strip at a predetermined speed sufficient to 130

permit the operator so to manipulate the edge of the shoe while in contact with the wheel 23 as to effect accurate and uniform laying of the foxing. The operator has 5 nothing to do except to properly manipulate the lasted shoe parts, starting and stopping the machine whenever desired by means of suitable treadle and clutch mechanism such as hereinbefore referred to. He 10 does not handle the foxing because the paper or cloth backing strip *b* acts as a conveyor to present the foxing to the shoe at the point where the shoe is placed in contact with wheel 23, the paper itself following partly 15 around said wheel 23 and then being rewound out of the way on the spool or reel 16.

Having now described my invention, I claim:

1. A machine for applying a rubber foxing to the lower margin of a lasted shoe having, in combination, a foxing-applying roller, means for causing a two-ply strip consisting of a foxing and a backing therefor to travel over the roller with the foxing outermost, and a guide located adjacent to the roller and adapted to engage the bottom of the shoe.

2. A machine of the class described having, in combination, means for applying to lasted portions of a shoe a two-ply strip comprising a foxing and a backing therefor, means for pressing against one edge portion of the backing to force one edge portion of the foxing against the shoe, means for removing the backing, and means for wiping down the other edge portion of the foxing.

3. A machine of the class described, having, in combination, means for applying to lasted portions of a shoe, a two-ply strip comprising a foxing and a backing therefor, means for applying pressure along one edge portion of the backing to lay one edge portion of the foxing, means for removing the backing, and means for applying to the foxing a succession of wiping operations to effect an even contact of the other edge portion of the foxing with the underlying shoe part.

4. A machine of the class described, having, in combination, means for directing against a lasted shoe a foxing and a flexible non-adhesive backing strip therefor, means for transmitting pressure through the non-adhesive strip to the foxing to cause the 55 foxing to adhere to the shoe, and a guide adapted to contact with the bottom of the shoe and to permit the shoe to be swung so that the foxing may be applied evenly around the whole lower margin of the shoe.

5. A machine for applying foxing to a shoe, comprising a presser, means for guid-

ing a foxing having a backing strip of non-adhesive material to said presser with the foxing outermost for presentation to the shoe, means for progressively separating said strip from the foxing and carrying it away, a wiper arranged in the rear of the presser, and means for operating the wiper.

6. A machine for applying foxing to a shoe comprising a presser, means for guiding 70 a foxing having a backing strip of non-adhesive material to said presser with the foxing outermost for presentation to the shoe, means for forming indentations in the foxing as it is fed, and means for progressively 75 separating the strip of non-adhesive material from the foxing and carrying it away.

7. A machine of the character described comprising a guide for a lasted shoe, means for delivering a strip of foxing to the shoe, 80 and an elastic rotary wiper for smoothing the foxing on to the surface which receives it.

8. A machine of the character described comprising a guide for a lasted shoe, means for delivering a strip of foxing to the shoe 85 and a rotary brush having bristles in separated groups for smoothing the foxing on to the surface which receives it.

9. A machine of the character described comprising a guide for a lasted shoe, means 90 for feeding a strip of foxing to the shoe, and means for forming stitch indentations in the foxing as it is fed.

10. A machine of the character described having a pair of co-operating wheels for 95 feeding a strip of foxing, one of said wheels having its periphery formed with projections to indent the foxing, and means for driving said wheels to simultaneously feed the foxing and indent it.

11. A machine of the character described comprising a wheel, means for guiding the foxing having a backing strip of non-adhesive material to said wheel with the foxing outermost for presentation to the shoe, means 105 for forming indentations in the foxing, a take-up reel for said strip to separate it from the foxing, and means for frictionally driving said take-up reel.

12. A machine of the class described having, in combination, means for applying to a lasted shoe a two-ply strip consisting of foxing and a backing therefor in such manner that the strip overhangs the edge of the shoe, means for pressing against the backing 115 and thereby laying one edge of the foxing, means for removing the backing, and means for wiping down the other edge of the foxing.

In testimony whereof I have signed my 120 name to this specification.

LOUIS A. CASGRAIN.
